UNITED STATES PATENT OFFICE.

CARL LITZENBERGER, OF DENVER, COLORADO.

DESIGN FOR A FLAG, BANNER, OR THE LIKE.

54,639.

Specification for Design.

Patented Mar. 9, 1920.

Application filed September 5, 1918. Serial No. 252,786. Term of patent 3½ years.

To all whom it may concern:

Be it known that I, CARL LITZENBERGER, a citizen of the United States, residing at Denver, in the county of Denver and State of Colorado, have invented a new, original, and ornamental Design for a Flag, Banner, or the like, as shown in the accompanying drawing and described in the following specification.

In the drawings,

Figure 1 is a view of new and ornamental design for flag, banner or the like, shown in elevation.

Fig. 2 is a view of the flag, banner or the like, in edge elevation.

The design comprises a stripe of blue indicated at 1, and a stripe 2 of red along the lateral edges of the banner separated by a field 3 of white. Extending across the field

3 and the two stripes 1 and 2 is a binding 4 the color of which forms no part of the present design. Across the bottom of the field 3 and the stripes 1 and 2 a fringe 5 is employed the color of which forms no part of the present design.

Located upon the white field 3 is a star 6. Located also upon this white field 3 is a shield comprising alternate red stripes 7 and white stripes 8 with a field 9 of blue with white stars 10, thereon.

Extending over the shield shaped figure are two figures representing shells point to point with the words "Over there" upon the two shells.

I claim:

The ornamental design for a flag, banner, or the like as shown and described.

CARL LITZENBERGER.
